UNITED STATES PATENT OFFICE.

WALTER I. TUTTLE, OF PROVIDENCE, RHODE ISLAND.

BEAM CONSTRUCTION.

1,249,559.

Specification of Letters Patent. Patented Dec. 11, 1917.

Application filed June 8, 1916. Serial No. 102,375.

To all whom it may concern:

Be it known that I, WALTER I. TUTTLE, a citizen of the United States, and a resident of Providence, in the county of Providence and State of Rhode Island, have invented an Improvement in Beam Construction, of which the following is a specification.

This invention relates to the construction 10 of warp beams and the like. One of the objects is to provide apparatus of the above type of simple and practical construction and efficient action. Another object is to provide apparatus of the above type in 15 which the parts are securely held in position and yet well adapted to meet the conditions of use in textile machinery. Another object is to provide apparatus of the above type of inexpensive construction and low 20 cost of maintenance in efficient condition. Other objects will be in part obvious and in part pointed out hereinafter.

The invention accordingly consists in the features of construction, combinations of 25 elements and arrangement of parts which will be exemplified in the structure herein-after described and the scope of the application of which will be indicated in the following claims.

30 In the accompanying drawing in which is shown one of various possible embodiments of this invention,

Figure 1 is an end view partially broken away to show the construction more clearly;

35 Fig. 2 is a sectional view taken along the line 2—2 of Fig. 1; and

Fig. 3 is a detail inside view of a head and associated parts.

Similar reference characters refer to 40 similar parts throughout the several views of the drawing.

Referring now to Fig. 2 of the drawing, there is shown in section the end construction of a warp beam, it being understood 45 that both ends are substantially identical, and one end only being shown in order to avoid encumbering the drawing. This warp beam comprises a central barrel or cylinder 1 which is rigidly constructed and may 50 be built up according to any desired specific form such as that indicated in my co-pending application Serial No. 102,369, filed June 8th, 1916. It may here be noted that 55 the term "cylinder" is used in a broad sense to denote broadly the body portion of a warp beam on which the material is wound and

beyond which the heads project in a radial direction whether such member be built up or integral.

Extending from end to end through the 60 cylinder 1 is a shaft 2 provided at each end with a journal 3 which is supported in a suitable bearing in the machine. The cylinder 1 at the end portion through which the shaft passes is recessed as at 4 and provided with an outer clutch ring 5 having the usual conical inner surface. This ring is secured to the cylinder in any desired manner to turn therewith.

65 Mounted upon the shaft 2 is a flanged hub 70 casting 6, the inner end of which projects within the recess 4 and terminates in a clutch portion 7 radially cut as along the lines 8, shown in Fig. 3 of the drawing. This clutch member mates with the clutch 75 member 5 within the cylinder 1 and is held in position by the lock nuts 9 threaded upon the shaft and bearing against the outer end of the hub. By these nuts 9, the pressure of contact of the clutch members is adjusted 80 and the parts locked in adjusted position.

85 On the flange 10 there is mounted a head member 11 preferably formed of sheet steel and provided with a central opening through which the hub 6 fits. The head member 11 is riveted as at 12 to the flange 10, thus being securely held in position at that point, and its outer surface bears firmly against the outer portions of the cylinder 1. The head member 11 extending past cylinder 1 terminates at its outer edge in a flange formed integral with its body and so shaped as to provide a belt race 13.

90 The sheet metal head portion 11 is preferably provided with a plurality of radial 95 ribs or beads stamped into the metal in a direction away from the cylinder 1 as indicated at 14.

100 Although the head portion 11 is of sufficient rigidity to make a firm engagement with the end of the cylinder 1, it nevertheless has a capacity for slight yielding to permit appreciable movement of the cast hub 6, thus permitting the pressure on the clutch to be adjusted or wear to be taken up. The sheet 105 metal member, moreover, is firmly and evenly urged against the barrel by the flange 10 about which it is secured and thus forms a light and yet strong head construction for the end of the beam. The pressure 110 on the clutch, however, is not restricted or limited by the lightness of this head con-

struction for it is brought to bear upon solid central hub castings and may thus be increased to any desired extent. In the action of the apparatus, the ends of the shaft 5 2 being mounted in suitable bearings, the beam is freely rotatable and its endwise or axial movement as a whole is limited by the nuts 9 which serve this purpose as well as the purpose above described. The beam is 10 driven by a suitable belt lying in the belt race 13 and from this race, the power is transmitted inwardly to the hub casting and thence through the frictional clutch to the beam itself. The sheet metal portion of the 15 head permits any desired diameter of belt race to be employed without waste of metal, and yet where the metal is needed in larger amount as to take up the heavy compression at the shaft, there is provided a casting 20 which effectively transmits the power to the beam. This form of head member accordingly has little inertia, thus being readily susceptible to changes in drive, and yet by the economical disposition of the metal, 25 makes an effective frictional connection with the beam which will permit relative rotary movement of these parts should the threads become entangled or for any other reason the load upon the beam become excessive.

30 The use of the apparatus will be largely obvious from the above description of its features of construction and action, and it may be noted that these features are especially adapted to meet the conditions of the hardest practical use in textile machinery.

As various possible embodiments might be made of the above invention and as various changes might be made in the embodiment above set forth, it is to be understood that all 40 matter herein set forth or shown in the accompanying drawing is to be interpreted as illustrative and not in a limiting sense.

I claim as my invention:

1. In construction of the class described, 45 in combination, a cylinder having a clutch portion formed in its end, and a two-part head, one portion of which co-acts with said clutch portion and the outer part of which is held by said first part against the outer portions of the end of said cylinder.

2. In construction of the class described, 50 in combination, a cylinder having a clutch portion formed in its end, and a two-part head, one portion of which is of cast metal and co-acts with said clutch portion, and the outer part of which is of sheet metal and is held by said first part against the outer portions of the end of said cylinder.

3. In construction of the class described, 55 in combination, a cylinder having a clutch portion formed in its end, a two-part head, one portion of which is of cast metal and co-acts with said clutch portion and is provided with a radially extending part, and 60 the outer part of which head is formed of

sheet metal and secured to the radially extending part of said cast metal portion to bear against the outer portion of the end of said cylinder, a shaft extending through said cast portion, and means adapted to 7 force the portions of said clutch together.

4. In construction of the class described, 75 in combination, a cylinder, a sheet metal head member having an edge portion shaped to form a belt race whereby it may be rotated, and a cast central member about which said first head member is secured and having a clutch portion thereon, said cylinder having at its end a clutch portion with which said first clutch portion co-acts.

5. In construction of the class described, 80 in combination, a cylinder having a clutch portion in its end, and a head provided with a clutch portion co-acting therewith, said head having its outer portions bendable relative to the central portion to bear evenly upon the outer portions of said cylinder when said central portions are clutched together.

6. In construction of the class described, 85 in combination, a cylinder, a sheet metal head member bearing against said cylinder, a shaft passing through said cylinder and through said head member, a central head member rigidly secured to said first member, and nuts threaded upon said shaft and bearing against said rigid central member to force it toward said cylinder.

7. In construction of the class described, 90 in combination, a cylinder provided with a clutch portion, and a head having its central portion in rigid engagement with said clutch portion and its outer portions yieldingly engaging the outer portions of the end 95 of said cylinder.

8. In construction of the class described, 100 in combination, a cylinder, a head having a cast central portion engaging the end of said cylinder and an outer sheet metal portion provided with a flange forming a belt 105 race, a shaft passing through said cast portion, and means on said shaft adapted to force said cast portion toward said cylinder.

9. In construction of the class described, 110 in combination, a cylinder having a clutch portion formed in its end, and a two-part head, one portion of which co-acts with said clutch portion and the outer part of which is held by said first part against the outer 115 portions of the end of said cylinder, said outer portion having formed integral therewith at its outer edge a belt race through which it is adapted to be driven.

10. In construction of the class described, 125 in combination, a cylinder having a clutch portion in its end, and a head provided with a clutch portion co-acting therewith, said head having its outer portions bendable relative to the central portion to bear evenly 130

upon the outer portions of said cylinder when said central portions are clutched together, and the outer portions of said head being bent into a belt race whereby it is 5 adapted to be rotated.

11. In construction of the class described, in combination, a shaft, a cylinder mounted on said shaft and provided with a clutch member positioned within a recess in one 10 end thereof, a cast hub member having a portion entering said recess and co-acting with said clutch member, and an outer

flange, means upon said shaft adapted to force said cast member toward said cylinder, and an annular sheet metal head member secured to the flange of said cast member and extending outwardly therefrom. 15

In testimony whereof, I have signed my name to this specification this 31st day of May, 1916.

WALTER I. TUTTLE.
